METHOD OF REVIVIFYING CLAY

Robert A. Carleton, Brooklyn, N. Y., assignor to
 National Electric Heating Co., Inc., New York,
 N. Y., a corporation of New Jersey

Application April 16, 1932, Serial No. 605,704

2 Claims. (Cl. 252—2)

This invention relates to the pyrogenic treatment of materials in a fine state of subdivision and particularly to a method and apparatus for treating a powdered or finely divided material suspended in a gaseous or fluid medium to promote some desired reaction, by heating the material and subjecting it to such supplemental treatment as is necessary to accomplish the reaction. Typical uses for this method and apparatus are found in the coking of coal, the refining of filtering materials, and the drying and roasting of cereals and other food products.

In the low temperature carbonizing and pre-treatment of coal for use in central stations and other plants where pulverized coal is fired under boilers for the generation of steam, the untreated coal contains many hydrocarbon compounds of relatively low value for the generation of heat but of relatively great value for many industrial and manufacturing uses.

It has been proposed to pretreat the coal to obtain these relatively high value by-products, extracting by means of heat, the oils and other volatile compounds and recovering the carbon in the form of coke to be burned under the boilers. By this means, with the coal and the by-products at a normal value and market, the value of the recovered by-products in the form of light and heavy oils, various hydrocarbon compounds and high calorific value gas suitable for illuminating gas enrichment and other purposes, will return a value which when credited to the cost of the coal will effect a substantial reduction in the net cost of the fuel burned for steam generating purposes.

The mechanisms heretofore employed for such heat treatment of coal have not been suitable for carbonizing the coal in a pulverized form, it being necessary to treat the coal in large and cumbersome brick retorts which are not only of high initial cost but for which the maintenance or upkeep and operating costs are also relatively great, and the space required is considerable; and the coke produced is in large masses and of a hard and refractory nature, requiring special and expensive apparatus for pulverization.

In such operation, due to the relatively long interval of time, usually 30 to 60 minutes, that the coal and its distillation products is exposed to the carbonizing temperature, the oils and other volatile compounds are cracked or decomposed by the prolonged heating to too great a degree, converting the more valuable oils and other products into relatively low value gas with the production

of lower value pitch or tar, and reducing the amount of coke recovered, and thus lessening the total value of the various products obtained.

The carbonizing retorts, due to their size and weight, require a relatively long time, usually 6 to 8 hours, to become heated to the required operating temperature and when shutting them down a large amount of stored heat is lost by radiation, and they are therefore not adapted to an intermittent method of operation.

Similar difficulties have been encountered in the burning and recovery for reuse of the clay and other material used for contact filtering and clarifying fluids, such as petroleum products and the like. The filtering material is in a finely divided state usually 85% passing through a 200-mesh screen, and great difficulty has been encountered because of the extreme fineness of the material and the relatively low differential in temperature between the oxidizing point of the carbon or other materials to be removed and the sintering or structural break-down point of the clay. Due to the difficulty or impracticability of controlling the temperature and other conditions under which the material is treated, closely enough, the structure and the absorbing efficiency of the recovered material is affected to the point that its reuse is not economically practical.

To overcome these difficulties and provide a satisfactory, economical process, I propose to pass the materials in a fluid suspension, through tubular heating devices directly heated by electrical current. This direct heating is preferably accomplished by passing electric current through the tubes which act as the heating devices and flowing the material to be treated through these tubes in a fluid suspension. The method of heating is especially important to the process because it may easily be controlled to treat the material rapidly at a high, but closely controlled temperature which causes the reaction to take place quickly and with a minimum of side reactions upon the products formed. Furthermore, the apparatus required is neither large nor expensive.

Upon leaving the heating devices, the material is cooled suddenly if desired and separated from the fluid suspending medium and from any vapors or gases extracted from it. These fluids, vapors, and gases are then appropriately separated and in some instances may be reused as a suspending medium for more of the untreated material. Suitable heat exchange may be made between the hot treated suspension and the cold untreated suspension.

With such a method, the material may be treated under a selected pressure, if desired, the length of time during which it is treated may be closely regulated by adjusting the rate of flow of the fluid suspension, and the temperature closely controlled by thermostats. The fluid suspending medium may contain a reagent which reacts with the material being treated or may contain a catalyst to aid the desired reaction.

10 The present invention finds particular utility at electrical power stations. In the operation of central electric power stations the load or power demand varies during different parts of the day, being very light during certain hours, such as 15 from midnight until morning, during which time large surplus electric generating capacity is available and electric current may be produced for any desired purpose, at a relatively low cost, as fixed charges and labor are already charged 20 against the plant and the only additional extra cost required for generating the electric current for coal pretreatment is substantially that due to the cost of the fuel required to generate the steam for use in the electric generators.

25 Preferably, the coal to be used is pretreated during the night or other suitable period when the demand for electric current is lowest and surplus electric generating capacity can be utilized, preparing the coal for the next day's run. The 30 amount of coal required will vary with the size of the plant, some of the larger city electric generating plants requiring 500 tons or more of coal per day.

Many of the modern electric generating plants 35 utilize steam boilers of several thousand boiler horsepower capacity each and are equipped with coal pulverizing and storage equipment, in which case the pretreatment or low temperature carbonizing of the coal is of particular benefit not 40 only as a means of reducing the net cost of the fuel used, by the sale of the recovered high value by-products, but also due to certain advantages of using pulverized coke over that of untreated pulverized coal, among which is not only the 45 greater combustion speed of the relatively pure carbon or coke, free from moisture and distillable compounds that usually slow down the combustion speed, but also from the consideration of safety, as there is considerable hazard in storing 50 pulverized bituminous coal due to the formation of explosive gases and the possibility of spontaneous combustion, which condition is not present in the handling and storage of pulverized coke.

55 In burning untreated bituminous coal, considerable smoke and gas is discharged from the stacks due to the presence of unconsumed hydrocarbon compounds; with the use of coke the volatile matter left in the coke is only that required to start combustion and rarely exceeds 6 to 8%, and which together with the relatively pure carbon is entirely consumed, resulting in the substantial elimination of smoke nuisance, and higher furnace efficiency.

60 The apparatus of the invention may be constructed in large or small capacities, of simple and rugged construction and arrangement, of metals resistant to the corrosive action of the 65 material being treated and that will be durable in service and operate efficiently and economically, that will not burn out or require replacement from overheating and that can be arranged to operate on any available electric heating current.

70 These and other features of the invention will

more fully appear from the following description and accompanying drawings and will be particularly pointed out in the claims.

For a detailed description and illustration of the preferred form of my invention, reference 5 may be had to the appended drawings and to the following description thereof. The embodiments of the invention, as illustrated in the drawings, are particularly suited for the treatment 10 of solid substances, such as coal and other carbonaceous materials, filter clays, and the like, that require a high temperature to obtain a desired reaction and that may be caused to flow through the heating tubes in a finely divided state, suspended in a suitable gaseous medium, 15 but it will be understood that this invention is not limited to the use of the arrangements shown in the drawings and that they may be readily modified within the scope of the invention to provide an efficient heat treating apparatus for many 20 industrial purposes where the material to be treated may be caused to flow in a fluid suspension through tubular heating means.

Preferred forms of apparatus embodying the 25 invention are illustrated in the accompanying drawings, in which Figure 1 is a plan view of an electric heating apparatus, embodying the principles of my invention.

Figure 2 is a side elevation of the device shown 30 in Fig. 1.

Figure 3 is a sectional view on line 3—3 of Fig. 2.

Figure 4 is a sectional view on line 4—4 of Fig. 2.

Figure 5 is an arrangement of apparatus especially suited for treating finely divided coal and 35 illustrates a method of separating and collecting the products distilled therefrom.

Figure 6 is an arrangement of apparatus for such operations as the reactivation of finely divided contact filter clays and the like.

As shown in the drawings, an electric heater is provided, comprising tubes 11 having walls of 40 relatively high resistance metal through which the electric heating current is caused to pass, the tubes thus acting as heating elements as well 45 as containers for the material undergoing the treatment. One or a plurality of such tubes may be employed to obtain the desired capacity, the internal cross sectional area of the heater tubes 11 and the thickness of the metal wall being 50 determined by the desired capacity, the pressure under which the system will operate and the 55 electric heating current available.

Preferably, the internal diameter of the heater tubes is such that the finely divided particles of 55 the material being treated and flowing through the tube will become quickly heated to the desired temperature, partly by direct contact with the heated walls of the tubes, but chiefly by the absorption of the radiant heat discharged from 60 the tube walls.

The gaseous medium used as a vehicle may be 65 of such a nature that it is neutral to and not effected by the material or it may be of such a nature that it will react with the material under the influence of the temperature and pressure involved, acting to cause a desired chemical or structural change to take place in the material.

The relative amount or volume of the gaseous 70 vehicle is determined by the weight, size and nature of the material treated, the results desired, the speed of flow, and the amount of dilution required.

The heater tubes 11 are provided with electric 75 terminals 12 welded or otherwise electrically con-

nected to a point substantially midway between the ends, by means of which the electric heating current is supplied. One end of each of the heater tubes 11 is connected to an inlet connection plate 13 of a separator 14, and the other end of each of the tubes is connected to a feeding mechanism 15, the members to which the tube ends are connected being grounded. The material which has been treated settles into a hopper 35 at the bottom of the separator and is removed by a screw conveyor 34 through a tube 42.

It will be observed that by so arranging the electric heating circuits the ends of the heater tubes 11 as well as the separator 14 and the feeding mechanism 15 and outer casing 16 are at ground potential, thereby eliminating any possibility of leakage of the electric heating current or the possibility of electric shock by contact with the apparatus.

20 Three heater tubes are shown in Figures 1 to 4 and by the use of a three-phase alternating current connected to the terminals 12, the currents in the three tubes being out of phase tend to neutralize the self induction thus increasing the 25 power factor to a maximum.

The heater tubes 11 are supported by insulating supports 17 of transite, fire brick or other suitable electrical insulating material that will withstand the temperature involved. An enclosing 30 casing 16 of steel plate or other suitable material is provided, the space between the casing 16 and heater tubes 11 being substantially filled with suitable heat insulating material 18 to reduce the loss of heat by radiation.

35 The feeding mechanism 15 with which the ends of heater tubes 11 communicate comprises a receptacle of steel or other suitable metal connecting by means of a duct 19 with a supply of pulverized coal. A suitable worm or screw feeding 40 device 20 operated by means of gears 21 and a driving pulley 22 causes the pulverized coal to be delivered to the inlet of heater tubes 11 at a regular and uniform rate.

A gas manifold 23 is provided, connecting by 45 means of an inlet 24 to the jets 25 placed at the inlet of heater tubes 11 through which gas or other suitable vehicle in sufficient volume is delivered under the desired pressure, causing the pulverized coal to become intimately mixed there- 50 with and to flow in a form of a cloud through the heating tubes 11. As the heater tubes are of relatively small internal diameter and their surface is heated uniformly to a selected high temperature, the finely divided material suspended in the 55 fluid vehicle is exposed to an atmosphere uniformly heated, chiefly by radiant heat and is quickly and uniformly raised to the selected reaction temperature.

The heater tubes may be supplied in relatively 60 long lengths, and correlated to the velocity of the solid and gaseous mixture to determine the interval of time the material is to be exposed to the effects of the heat.

Under certain conditions or when treating cer- 65 tain materials, it may be desirable to operate the heating tubes' surface at different temperatures at different portions of the tube length, for instance, to expose the material to a greater degree of heat during the first part of its travel through the heater tube, so as to raise it to the desired 70 temperature quickly, thereafter supplying sufficient heat only to maintain it at the selected reaction temperature during the balance of its travel through the heater tube. This may be

readily done by changing the wall thickness of the tube at different portions of its length or by using a metal having a different electrical resistance, the various sections being welded together. The electric current passing therethrough in series will cause heat to be generated in each section in accordance with its relative electrical resistance. Alternately, the electric terminals 12 may be connected to a point nearer the inlet end of the tube, whereby due to the lessened resistance at that end, more heating current will flow through the inlet end of the tube walls and more heat will be generated therein.

In certain instances, as when treating such materials as filter clays, it is desirable to quickly raise the material to the combustion or oxidation temperature of the carbon or other substance to be removed, then by the admission of air or other medium in controlled quantities, permit the heat of combustion or oxidation to furnish the balance of the heat required to complete the required reaction.

In such operations, it may also be desirable to provide means for cooling the flowing stream of gases and material to control the speed of the oxidation so as to prevent too rapid combustion and the generation of excessive heat that may cause disintegration or injury to the material. This cooling result may be readily obtained by causing the flowing stream of hot material to react by suitable heat exchanging means with the cold untreated material acting to cool the treated or partly treated material and heat the flowing stream of the cold material, thereby not only controlling the rate of the heat reaction but also acting to preheat the new or untreated material.

As shown in Figure 5, thermostats 26 may be provided, subjected to the temperature of heater tubes 11 and acting by means of controller 27 and voltage regulator 28 to regulate the electric heating current supplied heater tubes 11 and maintain the tube walls at a uniform, predetermined temperature.

Alternatively, a pyrometer may be subjected to the temperature of the material discharged from the heater tubes and operable directly to so regulate the electric heating current supplied the heater tube to maintain the material discharged at a selected temperature. An automatic device 29 is subjected to the pressure of the gas or vapor supplied inlet connection 24 and in the event the pressure of and consequently the volume of the gaseous vehicle supplied the apparatus becomes reduced to a predetermined degree, device 29 acts 50 to open control circuit 30 and by means of magnetic switch 31, interrupts the electric heating current supplied the heater tubes.

The apparatus shown in Figure 5 is designed particularly for the treatment of coal. In this 60 apparatus, the treated material is discharged from heater tube 11 to separator 14 of the well known centrifugal or cyclone type, where the solid material is separated from the gaseous vehicle and the various reaction products which when 65 distilling coal will consist of tar and oil vapors, ammonia, and various hydrocarbon gases and compounds, are discharged by means of outlet 33 to suitable apparatus commonly used for the separating and utilizing of such distillation products.

In some instances, it may be desirable to quickly cool the gases and solids to terminate the heat reaction, in which event the gaseous material may be caused to flow through a heat exchanger, not 75

shown, where they are reduced in temperature to the desired degree by heat exchange with a suitable cooling medium which may readily be of the same type of material as that being treated and which flows after being preheated through the heating tube for treatment.

From the separator 14, the distillation products flow through a pipe 45 to a heat exchanger 46, from there through a pipe 47 to a tar separator 48 and then through a pipe 49 to a fractionating tower 50. The gas escaping from the fractionating tower passes through a pipe 51 to an ammonia scrubber 52 from the outlet of which a part of the gas is returned to the jets 25 at the inlet end of the heater through a pipe 53, a pump 55, the heat exchanger 46 and a pipe 56. The discharged gases may be passed to any suitable recovery devices (not shown).

If it is desired to operate the heater under pressure, a weighted valve 57 may be placed at the outlet 33 of the separator, which valve will retard the flow of fluid so as to allow the desired pressure to be built up in the heater and separator.

25 Most of the tar, pitch, or other high boiling point compounds are condensed in the heat exchanger and may be removed through a connection 58 in the bottom thereof. The remainder, which pass in the form of a mist into the tar separator 48, are removed therein and pass out through a connection 59. The portions of the vapors which are fractionated out of the tower 50 are discharged through connections 60, 61 and 62 on the tower, and the ammonia is removed by a liquid circulated through the scrubber by a pump 63 through pipes 64 and 65. The remaining gases are discharged through a pipe 66 from which a portion of the gases are withdrawn for recirculation.

40 If desired, the coal may be mixed with the gases before they pass through the heat exchanger and also the gases to be discharged may be passed through the heat exchanger before discharging them.

45 The electric heater described in Figures 1 to 5 being of small mass or weight may be raised to the desired operating temperature and placed in operation within a period of 15 to 20 minutes and when shut down, the amount of heat stored 50 in the apparatus is negligible, thus making it particularly adapted for the intermittent method of operation required in the pretreatment of coal for central station and steam generating plants.

55 Due to its relatively simple arrangement and construction, the cost of the electrically heated coal carbonizing furnace is relatively low, being but a fraction of that of the cumbersome brick retorts heretofore employed. The amount of labor required for operation and maintenance is 60 slight and it can be installed in a small area or space, for example, a 50 ton per hour heater of the type shown in Figure 1 requires a floor space of but 3 by 50 feet, whereas the brick retort type of heater of the same capacity usually requires a 65 floor space of approximately 75 by 100 feet.

70 As the material being treated is exposed to the heat reaction for but a short interval of time which may, if desired, be less than one second, it may safely be exposed to much higher temperatures than would be practical when using methods involving relatively long exposure to the heat, and as the coal is in a finely divided state, usually 75 passing through a 200-mesh screen, the distillation reaction is practically instantaneous and

zone and are quickly cooled below the reaction temperature, secondary cracking of the vapors and the conversion of the more valuable primary products such as light oils into the less valuable gas, tar, etc., is substantially reduced, and as the 5 controlling elements of time, temperature, and pressure may be readily and closely controlled, the maximum yield of the desired products may be had on the most economic basis, that is, the balance between yield of coke, light and heavy 10 oils, and gas may be easily and quickly adjusted to suit the available market or demand.

The volume of gas used is such that the mixture of gas and pulverized coal will flow readily, with suitable separation between the particles of 15 coal, so that during the heating and distillation operation the particles of coal will not coalesce but will be delivered in substantially the same finely divided state; the amount of gas required 20 will vary, depending upon the type of coal, its volatile content, velocity of flow, temperature, and other determinable factors but will usually be at least 2 to 4 times the volume of the coal.

The section of the heater tube 37 adjacent to the inlet end may be heated to a greater degree 25 than the remainder of the tube so as to quickly raise the coal particles to the desired distillation temperature which may be from 950 to 1200° Fahr. depending upon the kind of coal treated and the products desired. The volatile oils and 30 other distillation products are immediately flashed or vaporized to the desired extent, and the products delivered in the form of finely divided coke, oil vapor, and other distillation products to the separator 14.

The particles of coal being separated by the gaseous vehicle will not coalesce or stick together as it goes through the softening period prior to distillation, the vapors leaving the coal particles 35 and converting it into coke.

It is desirable to retain a certain amount of volatile matter in the coke to facilitate ignition and rapid combustion in the furnace and therefore the temperature and other conditions controlling the distillation operation are so adjusted 40 that the coke, as delivered, will retain the desired amount of volatile matter, usually 6 to 8% being a suitable amount.

45 Under certain conditions, it is desirable to maintain the material under pressure during the reaction period, as I find that at certain pressures the secondary reactions may be better controlled and the yield of light oils and saturated compounds increased and that of gas reduced, and that under other pressure conditions the yield 50 of unsaturated compounds and gas may be increased.

55 It is therefore evident that by correlating the pressure to the temperature and duration of time the coal is under treatment that the proportions 60 and kind of products obtained by the distillation operation may be readily adjusted to suit the economic conditions or requirements of the period and the location of the plant. For instance, if a larger production of gas is desired, a longer period 65 of heating at a greater temperature at relatively low pressure would be used, the gas being produced at the expense of and by degrading or cracking the light oils and other distillation products. By the use of a shorter heating period at 70 a greater pressure, the secondary reactions may be reduced and a greater yield of light liquid products obtained with the consequent reduction in the amount of gas formation.

Figure 6 illustrates an arrangement of appa- 75

ratus for treating solid materials in a comminuted or finely divided form, such as contact filter clay, cement, etc., where the material may be caused to flow suspended in a suitable gaseous medium through the tubular heater, the operation being somewhat similar to that described in Figure 5 except the heat treatment is primarily intended for the purpose of effecting a structural change in the material rather than the recovery 10 of distillable compounds.

I have found that by heating such material in the type of tubular heater described, that due to the very exact and automatic control of the temperature, the duration of time and the condition 15 of the atmosphere in which the reaction takes place, that the carbon and other impurities can be oxidized and removed without substantial injury to the structure of the clay or other filter material.

20 I further find that by treating the clay under pressure with superheated steam in a slightly oxidizing atmosphere that the temperature required to oxidize the carbon is reduced and that the material may be delivered in a satisfactory condition suitable for reuse.

As shown in Figure 6, the relatively dry filter clay is delivered to the feeding mechanism 70 of the type described in Figure 1 where it is mixed with a suitable volume of gas supplied under a 30 suitable pressure by means of a blower, the finely divided clay suspended in the gaseous vehicle passing through a preheater 72, which comprises a double tube construction, the material passing through the annular space 73 provided 35 between the outer tube 74 and the inner tube 75 through which the hot material from the heater tube 76 is flowing, the cold untreated material serving to reduce the temperature and control the heat reaction of the material in the inner or 40 reaction tube to a suitable extent; itself becoming preheated and passing by way of a connection 77 and an insulated conduit 78 to the inlet 79 of the heater tube 76.

A jet 80 is provided, by means of which a selected volume of superheated steam is supplied the flowing stream of finely divided clay and gas, and by means of a jet 81 a determinate volume of air or other oxidizing medium is likewise supplied, the amount of steam and air admitted 50 being that required to complete combustion of the carbon and other combustible matter in the clay, at such a rate that complete combustion will take place while the clay is passing through the heater 76 and the reactor tube 75, but not 55 sufficient to cause too rapid a rate of combustion so as to raise the temperature of the clay to the sintering or melting point.

The mixture, with the combustible matter partly or wholly consumed, passes from the end of 60 the heater tube 76 to the reactor tube 75 of the heat exchanger 72 where the combustion of the carbon is completed, being gradually cooled by heat exchange with the cooler untreated material passing through the annular space 73 and is then 65 discharged to a suitable separator 82, preferably of the usual centrifugal type, where the solid material is removed by means of screw device 83 and a discharge pipe 84, the gas and products 70 of distillation and combustion passing to a suitable scrubber 85 and to the gas recovery system, not shown.

A jet 86 at the entrance to the reactor tube 75 is provided, whereby additional air or other oxidizing medium may, if necessary, be added to

accelerate or continue the combustion of the carbon.

As in the treatment of pulverized coal described in Fig. 5, due to the relatively high temperatures involved, the thermal reactions are extremely 5 rapid and it is very essential that the elements of temperature, time, pressure, and atmospheric conditions, all of which factors influence the condition in which the material is delivered and its value for reuse, be properly correlated and closely 10 controlled.

Due to the relatively small mass and weight of the heater tube 76 the walls of which comprise the heating elements, it responds very quickly to any change in the value of the heating current 15 supplied, and by means of the sensitive pyrometer controlling device 87 and the voltage regulator 88, may be readily and automatically maintained within a variation of approximately 2° Fahr. of the selected operating temperature. The pressure under which the reaction proceeds is automatically regulated by a loaded valve 57 and as the clay or other material to be treated is supplied in a uniform and regular manner, after the apparatus is once adjusted to suit the required operating conditions, it will thereafter operate with 20 but slight further attention.

The electric heating current may be supplied from any suitable source, either direct or alternating but the drawings show the heater connected to a 3-phase electric power circuit; and the connections and controls being similar to those shown in Figure 5, will not again be described.

While but a single heater tube is shown in Figure 6, it is obvious that any desired plurality of such tubes may be employed, in a manner substantially as shown in Figure 5, and that while the heater tubes are shown in relatively long straight sections, they may readily be constructed 35 in a spiral or other desired form or arrangement.

When treating certain materials, it may be desirable to introduce into the flowing stream of such material a suitable reagent, which may be in a gaseous form as hydrogen or compounds that liberate hydrogen at high temperatures, these constituents being introduced alone or combined with any suitable liquid or solid substance to effect a desired reaction in the material being treated. Such a catalyst or substance may be 45 readily introduced into the flowing stream by means of a suitable mechanism such as a pump or measuring device by way of inlets 80, 71, or 86.

While the invention has been described particularly with reference to the treatment of finely divided coal and filter clays, it is obvious that its use may be extended to other fields in which it is desired to treat and process various forms of material that may be caused to flow through tubular heating means in a fluid suspension.

It is also obvious that many other embodiments of the invention may be made by those skilled in the art, and it will be therefore understood that the particular devices and arrangements shown and described are of an illustrative character and are not restrictive and that various changes in form, construction, arrangement in parts and methods of use may be utilized within the spirit and scope of the following claims.

What I claim is:

1. The method of continuously purifying comminuted filter clay contaminated with carbonaceous material, which comprises suspending the material in a gaseous medium which is substantially non-oxidizing at operating temperatures, 75

flowing the suspended material in a closely confined stream, subjecting each increment of the said stream to the influence of radiant heat for a period of less than a few seconds, subjecting 5 said stream to the influence of a gaseous medium introduced to pass in the direction of flow to cause oxidation of the carbonaceous material at operating temperature, removing the said stream from the heating influence and separating the solid 10 from the volatile products of said reaction.

2. The method of continuously purifying comminuted filter clay contaminated with carbonaceous material, which comprises suspending the material in a gaseous medium which is substan-

tially non-oxidizing at temperatures between 950 and 1200° F., flowing the suspended material in a closely confined stream, subjecting each increment of the said stream to the influence of radiant heat for a period less than a few seconds to heat 5 the material to a temperature within the range of 950 to 1200° F., subjecting the said stream to the influence of a gaseous medium introduced to pass in the direction of flow to cause oxidation of the carbonaceous material under the afore- 10 mentioned conditions, removing the said stream from the heating influence and separating the solid from the volatile products of said reaction.

ROBERT A. CARLETON.
